UNITED STATES PATENT OFFICE.

ABRAHAM HARRIS, OF NEW YORK, N. Y.

CLASP FOR SUSPENDERS.

1,142,957.

Specification of Letters Patent. Patented June 15, 1915.

Application filed May 28, 1914. Serial No. 841,595.

To all whom it may concern:

Be it known that I, ABRAHAM HARRIS, a citizen of the United States, residing at New York, in the county of New York and State of New York, have invented certain new and useful Improvements in Clasps for Suspenders; and I do declare the following to be a full, clear, and exact description of the invention, such as will enable others skilled in the art to which it appertains to make and use the same.

This invention relates to new and useful improvements in clasps and more particularly to a clasp applicable for use on suspenders whereby the use of buttons may be eliminated on the devices with which the suspenders are adapted to coöperate.

A further object of the invention resides in providing a clasp which is also applicable to other uses than that aforementioned but which in any use may be quickly and readily applied and removed when desired.

A still further object resides in providing a clasp which is simple and durable in construction, inexpensive to manufacture and one which will be very efficient and useful in operation.

With these and other objects in view my invention consists of the novel features of construction, combination and arrangement of parts as will be hereinafter referred to and more particularly pointed out in the specification and claims.

In the accompanying drawing forming a part of this application: Figure 1 is a rear elevation of a device constructed in accordance with my invention and applied to use: Fig. 2 is a front elevation thereof: Fig. 3 is a side elevation of the same: Fig. 4 is a longitudinal section therethrough, as seen on line 4-4, Fig. 1: Fig. 5 is a similar view showing the clasp in its ineffective position: Fig. 6 is a transverse section as seen on line 6-6, Fig. 1: and, Fig. 7 is a perspective view of the clasp proper, removed.

In describing the invention I shall refer to the drawing in which similar reference characters designate corresponding parts throughout the several views and in which 50 1 indicates a body plate formed of metal or other material bent upon itself to form the front and rear portions 2 and 3 respectively. At the looped portion of this body 1 which forms the portions 2 and 3, said latter portions abut one another as indicated at 4 and the rear portion 3 continuing from this

contacting or abutting portion is offset as indicated at 5 whereby to position said portion or plate section 3 in spaced relation to the front plate like section 2 of the device. 60 This abutting portion 4 of the plate like sections of the body is provided with a slot indicated at 5 through which is passed the tab or tape 6 of a suspender or the like so that the open end of the U-shaped body 65 which is formed by the bending of the plate in the manner above described, forms the lower or receiving end of the device.

The front plate section or the like 2 of this body is cut out to form an opening 7, 70 the latter tapering smaller toward its lower end, for a purpose to be hereinafter and more particularly set forth. This opening 7 is somewhat triangular in design the side walls of which are arcuately designed. 75

The rear plate like section 3 of this body 1 is provided about centrally with a vertical slot 8 which continues from a point adjacent the lower end of the plate 3 to the offset portion 5 thereof. The side edges of 80 the plate like section 3 continuing from the offset portion 5 to the lower edge thereof are bent forwardly to provide flanges or the like 9.

The aforementioned body 1 forms a support or coöperating portion for my clasp which is indicated as 10. This clasp 10 is generally of L-shaped design formed preferably of a single strip of metal and at the junction of the arms thereof are provided 85 the integral and laterally extending arms 11, the extreme free ends of which are reduced and pivotally received in the flanges 9 of the plate like section 3. Thus it will be seen that this clasp proper is pivotally supported 90 in the rear plate like section of the body member and is so disposed as to permit the longer arm section indicated as 12 to project through the slot 8 of the plate like section 3 while the shorter arm section which is indicated as 13 in the drawing is adapted to 95 project through the opening 7 in the plate like section 2 of the body.

The clasp proper is so pivoted on the body as to permit the upper end of the longer arm 105 12 to terminate at the offset portion 5 of the plate like section 3 and at this upper or outer end of said arm 12 is provided a T-shaped head 14 which forms a finger piece thereon. This head or finger piece 14 is adapted to be 110 received on the offset portion of the plate like section 3 when the lever or clasp 10 is

2

raised, and in this position the longer arm 12 will fit flush with the outer face of the 5 plate like section 3 of the body. The T-shaped head or finger piece 14 is however slightly bent outwardly so as to be more readily engaged by the fingers when it is desired to lower the same or dispose the clasp to its ineffective position and to aid this engagement by the fingers, the upper 10 edge of said T-shaped head is corrugated or otherwise roughened as indicated at 15. The opposite or shorter arm 13 of this L-shaped clasp 10 is, as stated above, adapted to project through the enlarged opening 7 in the opposite face or plate like portion 2 of the body and this portion 13 has the side edges thereof notched as indicated at 16 whereby a portion of the garment or other material to which this is applied may be received therein in the application of the clasp 20 to its effective position. When the lever or clasp 10 is disposed to its ineffective position, that is when the arm portion 12 thereof is lowered with respect to the plate like section 3 the opposite arm section 13 will be raised and the material may be inserted through the open end of the body 1. Upon the disposition of the clasp to its opposite position, that is upon the raising of the 25 arm section 12 of said clasp or lever, the opposite arm 13 thereof will be forced against the material, thus forcing a portion thereof through the triangular shaped opening 7 of the opposite face or plate like section 2 of the body. It is obvious that portions of the 30 material will be received in the notches 16 of said arm 13 and inasmuch as this opening 7 tapers smaller toward its lower end the garment or material will be clasped 35 tightly therein and the clasp or lever properly indicated as 10, will be retained in its effective engaging position. In order to release the clasp from its engagement with the garment or other goods to which same is applied it is only necessary to engage the head or finger piece 14 on the upper or outer end 40 of the arm 12 and draw outwardly and downwardly thereon. This operation releases the engagement of the clasp properly 45 from the material and said clasp may be entirely disengaged from the garment or material.

It will be seen from the above description of the construction and operation of the device that the clasp is one which is particularly well adapted for use in connection with suspenders in the application of the same to garments without the use of buttons. It will furthermore be seen that the same is 55 equally well adapted for use in other connections wherein clasps are necessary and

in any use thereof, it will be appreciated that the same may be applied and removed quickly and readily.

It will still further be seen that the device is one which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to, within the scope of the appended 75 claims, without departing from the spirit or sacrificing any of the principles of the invention.

Having thus described my invention what I claim is:

1. A fastener of the class described comprising a U-shaped body, one arm of which is provided with an opening tapering toward its free end, and an angular clasp pivoted on the other arm thereof, one member of said clasp being positioned for projection through said tapered opening and having curved notches in the side edges thereof whereby, when said clasp is closed, the notched member thereof will be forced 90 through said tapered opening in the arm of the body and downward into locking engagement with the converging walls of said opening, the outer ends of said curved notches serving to retain a material disposed 95 between the arms of the body in engagement with said clasp.

2. A fastener of the class described comprising a U-shaped body, one arm of which is provided with a slot and the other with a 100 triangular shaped opening having the apex thereof extending toward the free end of said arm, and an angular clasp fulcrumed adjacent the junction of its members on the arm of said body having the slot therein to 105 permit the members of the clasp to project respectively into the slot and through the triangular opening of the arms of the body, the member of said clasp projecting through the triangular opening in one arm of the body having inwardly curved notches on the side edges thereof and adapted to be forced into binding engagement with the tapered walls of said triangular opening and secure material disposed between said body arms. 110

In testimony whereof I have hereunto set my hand in presence of two subscribing witnesses.

ABRAHAM HARRIS.
